UNITED STATES PATENT OFFICE.

EMMA G. HINTZ, OF READING, PENNSYLVANIA.

CORSET.

No. 899,165.

Specification of Letters Patent.

Patented Sept. 22, 1908.

Application filed January 26, 1907. Serial No. 354,176.

To all whom it may concern:

Be it known that I, EMMA G. HINTZ, citizen of the United States, residing at Reading, in the county of Berks and State of Pennsylvania, have invented certain new and useful Improvements in Corsets, of which the following is a specification.

This invention relates to improvements in corsets and the object of the present invention is to provide a permanent, elastic connection between the two members of a corset.

The invention consists of a plurality of elastic bands permanently secured to both members, arranged diagonally in pairs and crossing each other approximately midway of their length. The object being to overcome the necessity of lacing the members which operation is tedious and unsatisfactory by reason of a lack of uniformity.

20 In my construction the eyelets are dispensed with.

In the method of joining the corset members heretofore generally in use, that is, by means of a lacer or cord, the breaking thereof will interfere with the comfort of the wearer as the entire connection between the two members is effected, while with my present construction, even should one of the bands break the members would still be sufficiently 30 well secured. The principal object being to insure the comfort of the wearer.

The construction herein shown will permit more freedom in movement as the strain will be distributed and not confined to any single 35 point.

The invention is more fully described in the following specification and clearly illustrated in the accompanying drawing which shows the connecting ends of two members 40 of a corset with my invention applied thereto.

The numeral 1 designates the corset members and 2 the connecting bands by means of which they are joined together.

In the drawing I have shown a series of 45 three pairs of these bands though it is evident that any number may be employed, it being preferable however to use an odd number so that one pair will be located at the

middle or approximately so. These bands may be made of any suitable material, preferably elastic, and their ends are permanently secured to the edges of the corset members in any desired manner. Each band is arranged diagonally from one member to the other and they are arranged in 55 pairs one of which crosses the other about midway of its length. Each band is free from connection with the other or crossing band, thus allowing free movement of each band.

60 It is evident that the movement of the corset members, due to the different positions assumed by the wearer, will be free and easy; that the strain will not be confined to any one point; that the corset members will always 65 return to their normal position when the body is moved and, that, inasmuch as there are no rubbing points or other friction, as with the lacer in the eyelet, the tendency to break is decidedly lessened if not entirely 70 overcome, thus lengthening the life of the corset, while the accidental breaking of one of the bands will not materially affect the others nor the comfort of the wearer.

Having thus fully described my invention, 75 what I claim and desire to secure by Letters Patent is:—

A corset comprising side members elastically held together at the back by a plurality of pairs of elastic diagonal bands of uniform 80 length and width, said bands being permanently secured at both ends to the back of the corset members, one band of each pair crossing the other loosely midway of its length, said bands being spaced apart at their points 85 of attachment with the side members and being directly disconnected from each other along their entire lengths.

In testimony whereof I have signed my name to this specification in the presence of 90 two subscribing witnesses.

EMMA G. HINTZ.
